UNITED STATES PATENT OFFICE.

ROY V. COLLINS, OF NEWTON, MASSACHUSETTS, ASSIGNOR TO THE WEST NEWTON COMPANY, OF WEST NEWTON, MASSACHUSETTS, A CORPORATION OF MASSACHUSETTS.

ELECTRIC BLOCK-SIGNAL SYSTEM.

1,286,946.

Specification of Letters Patent. Patented Dec. 10, 1918.

Application filed February 7, 1916. Serial No. 76,833.

To all whom it may concern:

Be it known that I, ROY V. COLLINS, a citizen of the United States, residing at Newton, county of Middlesex, State of Massachusetts, have invented an Improvement in Electric Block-Signal Systems, of which the following description, in connection with the accompanying drawing, is a specification, like characters on the drawing representing like parts.

This invention relates to electric block signal systems such as are used on electric railways for controlling traffic, and the principal object of the invention is to provide a novel electric block signal system of the counting-in and counting-out variety which is constructed to give signal indications in accordance with the standard practice in use on steam railways, that is, to give a "proceed" signal either in the form of a green light or a semaphore arm in vertical position to a car entering the block when the block is clear; to give a "proceed with caution" signal either in the form of a yellow light or a partially-raised semaphore arm to a car entering a block when there is another car in the block proceeding in the same direction; and to give a "stop" signal either in the form of a red light or a horizontal semaphore arm to a car entering the block when the traffic rules require that said car should not enter the block.

In most block signal systems for electric railways of the so-called counting-in and counting-out type, that is, systems that register successive cars into a block and then register or count said cars out of the block as they leave the block, some means are provided for giving indication to the motorman as he enters the block that he has been properly registered or counted in. This is usually done by causing the signal to give some momentary indication at the time that the counting device operates, such, for instance, as the flash of a signal light, or the momentary movement of a semaphore arm. In order that the motorman may get this indication, however, it is necessary for him to keep a close watch on the signal as he is entering the block, for the signal has the same appearance both before and after the indication, and the only way that the motorman can determine whether he has been counted in or registered in the block properly is by noting the momentary indication.

This is sometimes difficult to do because if the motorman's attention happens to be diverted at the instant that the indication is given so that he will not see this indication, he will not be able to tell from the signal itself whether or not he has been properly counted in.

My invention provides a signal system in which the signal gives a different indication after a car has been counted into the block than it does prior to that time, and the indication that is given conforms to the standard railway signal practice. The signal guarding the block normally gives the "stop" indication, and as the car enters the block, if it is properly counted in, the signal will give either a "proceed" or a "proceed with caution" indication, depending on whether the block ahead is clear or is already occupied by another car proceeding in the same direction, but the change in the signal from the "stop" indication to the "proceed" or "proceed with caution" indication will indicate to the motorman that he has been properly counted into the block. If the counting device does not properly operate to register the car into the block, then the signal guarding the block will maintain its "stop" indication, thus showing to the motorman that his car has not been counted into the block. He will then back out of the block and make another entry. With my signal, the motorman simply has to follow the indication which the signal gives, that is, to proceed when the signal gives a "proceed" indication, to proceed cautiously when the signal gives the "proceed with caution" indication, and to stop when the signal gives the "stop" indication, and he does not have to watch for any special indication to know whether his car is counted into or is counted out of the block properly.

Another object of the invention is to provide a signal system so constructed that the signals will not be disturbed or changed by any crossed wires, broken wires or abnormal occurrence that would throw current onto or take it off from the line wires of the signal system, but will only be changed or operated by cars entering or leaving the block. I accomplish this object by providing a signal system in which the signals can be set only by the closing of two contacts in rapid succession and in a predetermined sequence and arranging the system

so that a car entering or leaving the block will close the contacts in this predetermined manner. There is practically no possibility that the circuits could be closed in just this predetermined manner by the occurrence of any abnormal condition, such as crossed wires, broken wires, etc., and as the signals of the system can only be set or restored by the closing of the two circuits in this predetermined manner, there is no danger that the signal system will be upset or interfered with by the occurrence of any abnormal conditions.

Other objects of my invention are to provide an improved block signal system which is so constructed that when the last one of a predetermined number of cars have entered the block successively, all of the signals guarding the block will display the "stop" indication and will maintain such indication until some of the cars have left the block; to provide an improved block signal system which is so constructed that if a motorman overruns a "stop" signal and enters the block, he will receive a proper indication to indicate that his car was registered into the block and when he backs out of the block, the signals will be returned to the condition in which they were before he overran the signal; to provide a block signal system which is so constructed that if a car accidentally overruns a "stop" signal set against it, but fails to become registered into the block in so doing, it will also fail to register out of the block when it backs out of the block; to provide a block signal system which is extremely flexible in its operation and will give proper protection to the cars in the block under any abnormal conditions which may arise, and otherwise to improve block signal systems, all as will be more fully hereinafter set forth.

In order to give an understanding of my invention, I have illustrated in the drawings a selected embodiment thereof which will now be described, after which the novel features will be pointed out in the appended claims.

Figure 1 of the drawing is a diagram view of the wiring of the signal box at one end of a block;

Fig. 2 is a similar view showing the wiring of the signal box at the opposite end of the block, it being understood that Figs. 1 and 2 constitute together the system protecting one block;

Fig. 3 is an enlarged view of one of the magnets used for operating the signal;

Figs. 4, 5, 6, 7, 9, 10, 11 and 12 are diagram views showing some of the different indications that are given as the cars proceed into and through the block;

Fig. 8 is an enlarged view of the counting-in and counting-out wheels of the car counting mechanism;

Fig. 13 is a diagram view of a modification hereinafter referred to.

I have herein shown my system as it might be installed for protecting a block constituted by a length of single track having a turn-out at each end, although with proper modifications the system could be applied to any block system.

1 indicates the trolley wire of the block which extends between two turn-outs 2 and 3, the turn-out 2 having the two branch trolley wires 4 and 5, and the turn-out 3 having the two branch trolley wires 6 and 7. The signal herein illustrated is arranged to use lamps for giving the signal indication, a green light constituting the "proceed" signal, a yellow light constituting the "proceed with caution" signal, and a red light constituting the "stop" signal, this being in accordance with standard railway signal practice. There is a signal mechanism at each end of the block as usual in block signal systems, and these signal mechanisms are connected by two line wires 8 and 9, 8 being the signal line wire and 9 the signal-restoring line wire.

The signal mechanisms at each end of the block comprise two signals, those at one end of the block being designated 10 and 80 respectively, and those at the other end of the block being designated 11 and 80. The two signals 80 are herein shown as two-light signals, each comprising the red light 85 and the yellow light 79. The signals 10 and 11 are shown as three-light signals, each comprising the green light 12, the yellow light 13 and the red light 14, although said signals 10 and 11 might be two-light signals without departing from the invention. The signals 10 and 11 normally show the red light, thus giving the "stop" indication, while the two signals 80 normally show the yellow light, thus giving the "proceed with caution" indication. Each signal 80 is so situated that a car entering the block will pass it before it has fully entered the block and before it passes the signal 10 or 11. These signals 80 are for the purpose of indicating to a motorman of a car approaching the block whether or not he is to enter the block and the signals 10 and 11 are for the purpose of indicating to the motorman of a car entering the block that his car has been properly registered into the block, and also for the purpose of displaying a "stop" indication when a car has entered the block thereby to give said car protection. As stated above, the signals 80 normally show the yellow light, while the signals 10 and 11 show the red light. As a car approaches the block from either end it will pass the signal 80 if the latter shows the yellow light, thus giving the "proceed with caution" indication, and as it proceeds the light in the signal 10 or 11 will be changed from red to

green if there is no car in the block, and will be changed to yellow if there is a car already in the block traveling in the same direction. When the motorman reaches the 5 signal 11 he observes whether it shows a green or a yellow light, and if it shows either of these lights rather than a red light, he knows that his car has been counted into the block and he then proceeds past the signal 10 or 11. If, however, the signal 10 or 11 continues to show a red light only, he knows that his car has not been properly counted into the block. It is not necessary for the motorman to see either signal 10 or 15 11 change from the red to the green or the yellow light. It is simply necessary for him to observe whether it shows a green, a yellow or a red light and to act accordingly.

If the signal 10 or 11 shows green or yellow, the motorman will proceed into the block past said signal, and as he does so, said signal will change to red again thereby giving proper protection. The counting of the cars into and out of the block is performed 20 by a counting-in and counting-out mechanism which will now be described, it being understood that the mechanisms at the two ends of the blocks are similar, so that a description of one will suffice for both. This 25 mechanism comprises a counting-in wheel 15 mounted on a shaft 16 and a counting-out wheel 17 also mounted on said shaft. The counting-in wheel is advanced one step forward each time that a car enters the block 30 by means of a signal-setting magnet 18. The counting-out wheel 17 is also advanced one step each time that a car leaves the block at the opposite end by means of a signal-restoring magnet 19. In Figs. 1 and 2 this 35 40 45 counting mechanism is shown partly in elevation and partly in plan view so as to better illustrate it. The counting-in and counting-out wheels 15 and 17 are shown in side view adjacent the magnets 18 and 19 and are also shown in plan view so as to illustrate the operation of the stepped cam 20 and the contact member 23.

The counting-in wheel 15 is provided on its face with a stepped cam 20 which is engaged by a roll 21 carried by the counting-out wheel 17. Said counting-out wheel 17 is slidably mounted on the shaft 16 and is acted upon by a spring 22 which keeps the roll 21 in contact with the cam 20 or with the face 50 55 of the wheel 15. This counting-out wheel 17 controls the position of a contact member 23 which in turn controls the circuits for the lamps 12, 13 and 14 of the signal 10, all as will be more fully hereinafter referred to.

60 The signal-setting magnet 18 is actuated to step the counting-in wheel forward one step as the trolley of a car is passing along the branch trolley wire 4 preparatory to entering the block 1, and the signal-restoring magnet 19 is energized to step the signal-restor-

ing wheel 17 forward one step when the car leaves the block along the branch trolley 6. The branch trolley wires 4 and 5 have contactors 24 and 25 associated therewith, and the branch trolley wires 6 and 7 have contactors 26 and 27 associated therewith. The trolley wire 1 also has contactors 28 and 29 associated therewith at the respective ends and adjacent the signals 10 and 11. These contactors will be more fully hereinafter described. 70 75

When the block is free of cars, the counting-in and counting-out wheels have the relative position shown in Fig. 1. As the trolley passes along the trolley wire 4 going to the right, it actuates a contactor 24 thereby to energize the signal-setting magnet 18, and this results in stepping the signal-setting wheel 15 at the left end of the block forward one step. This brings the second or intermediate step of the stepped cam 20 opposite the roll 21, and the spring 22 then forces the counting-out wheel 17 longitudinally of the shaft 16 as far as the second step of the stepped cam 20 will permit. This results in 80 moving the contact member 23 into its intermediate position, in which circuit connections are made that bring the green light 12 of signal 10 into the circuit so that the motorman will then get a "proceed" signal, and he will then enter the block. As he passes the contactor 28 the green light 12 will be extinguished and the red light 14 of signal 10 will be lighted, thus giving his car proper protection. It will be understood, of course, 85 that the red light is maintained at the opposite end of the block. As the car leaves the block over the branch trolley wire 6, the trolley thereof will actuate the contactor 27 which will result in actuating the restoring magnet 19 at the left or entering end of the block, thus advancing the restoring wheel 17 and bringing the wheels 15 and 17 back into their initial relative position. This results 90 95 100 in restoring the signals to their normal condition. If, however, a second car starts to enter the block from the left while the first car is still in the block, then when the second car passes the contactor 24, the magnet 18 will be energized to step the counting-in 105 wheel forward a second step which will carry the stepped cam 20 out from engagement with the roll 21 and allow the counting-out wheel 17 to move longitudinally of the shaft 16 to bring the roll into contact with the face of the wheel 15. This will bring the contact 23 into the lower dotted line position Fig. 1 and will close circuit connections leading to the yellow lamp 13 so that the second car will have a "proceed with caution" signal displayed. The motorman will then enter the block, but with the knowledge 110 115 120 that another car is in the block ahead of him traveling in the same direction. When the second car passes the contactor 28 the circuit 125 130

connections will be made which will show the red lamp 14 at the signal 10, thus giving the second car proper protection. When a third or fourth succeeding car enters the 5 block, before the first car leaves the block at the opposite end, said third or fourth car will actuate the contactor 24, thus stepping the counting-in wheel 15 forward, and this 10 operation will cause the signal 10 to display a yellow light which will be changed to red when said succeeding car passes the contact 28. As the cars leave the block, the counting-out wheel 17 at the entering end of the 15 block will be advanced one step for each car so that the signal will be restored to its normal condition when the cars have all passed out of the block. The motorman, therefore, merely notes whether his signal 10 gives a "proceed" indication, a "proceed 20 with caution" indication or a "stop" indication, and he acts accordingly, and the change from the red or "stop" indication to either the "proceed" or the "proceed with caution" 25 indication, indicates that the car has been properly counted into the block by actuating the contactor 24.

The signal-setting and signal-restoring magnets 18 and 19 at each end of the block are so constructed that they will not be operative to step the signal-setting or signal-restoring wheels forward except when they 30 receive two current impulses in rapid succession, one of which is a light current and the other of which is a heavy current, and 35 the contactor that I employ and the circuit connections from the contactor to the magnets are such as to provide this light and then heavy current in rapid succession whenever the contactor is actuated. Each 40 contactor herein shown is similar to that illustrated and described in my copending application Se. No. 61,493, filed November 15, 1915, and as no claims are made herein to the contactor, I have shown it in diagram 45 only. The contactor 24 for controlling the signal-setting magnet 18 comprises a contact arm 30 pivotally mounted at 31 to a standard 32 carried by the trolley wire and constructed so that as the trolley passes 50 under the trolley wire it will cause the contact arm 30 to swing upwardly into the dotted line position. During this upward movement the contact arm wipes by two contacts 33 and 34. The contact arm 30 is 55 electrically connected to the trolley wire and, therefore, when it moves upwardly past the contacts 33, 34 first the contact 33 and then the contact 34 will be connected with the trolley wire. The contacts 33 and 60 34 are both connected to a signal-setting magnet 18, the contact 33 being connected by what I have called a preliminary circuit, and the contact 34 being connected by what I have called a secondary circuit. The pre-

liminary circuit has a greater resistance 65 therein than the secondary circuit so that when the preliminary and secondary circuits are closed by the upward movement of the arm 30, the magnet 18 will be subjected to first a light and then a heavy current. 70 The preliminary circuit comprises the contact 33, wire 35, sectional resistance 36, wire 37, counting-in wheel 15 which is connected to the drum 39 by the contact pawl 38, wire 40, magnet 18 and wire 41 to the ground. 75 The secondary circuit leading from the contact 34 comprises the wire 42, magnet 43, which will be presently described, wire 44, which connects to the sectional resistance, a portion only of said resistance, wire 37, 80 counting-in wheel 15, drum 39, wires 40 and 41 to ground. As a result of these circuit connections when the arm 30 moves upwardly and engages the contact 33, the preliminary circuit comprising wire 35, resistance 36, wires 37, 40 and 41, is closed through the signal-setting magnet 18, which circuit includes all of the resistance 36, and almost immediately thereafter, the secondary circuit 85 is closed by the engagement of the contact arm 30 with the contact 34, said secondary circuit including only a portion of the resistance 36: As a result, the magnet 18 is subjected momentarily to two successive current impulses, one of which is light 95 due to the closing of the preliminary circuit, and the other of which is heavy due to the closing of the secondary circuit. The signal-setting magnet is designed so that it will only operate to step the counting-in 100 wheel 15 forward when it receives these two current impulses in rapid succession, and in this predetermined sequence, that is, first a light and immediately after a heavy current. Said magnet is provided with a relatively-large main armature 46 and a relatively-small auxiliary armature 45, the auxiliary armature 45 being pivoted to the bracket 47 at 48, and the main armature 46 being pivoted thereto at 49. The bracket 47 also 105 has pivoted thereto at 50 a locking member 51 which normally occupies a position to lock the armature 46 from being moved upwardly when the magnet 18 is energized. This locking member 51 carries a projection 110 or finger 52 adapted to be engaged by the tail 53 of the small auxiliary armature 45 so that if the main large armature 46 remains at rest and the small armature 45 is attracted toward the magnet, the tail 53 of 115 said armature will engage the projection 52 and swing the locking member 51 backwardly out of engagement with the tail of the large armature 46, as seen in Fig. 3. The large armature is thus free to be moved 120 upward only during the time interval when the locking member 51 is swung backwardly and before said member swings forwardly 125

again into its normal position. These armatures 45 and 46 of the magnet 18 are so designed that the smaller armature only will be attracted when the magnet 18 is energized from the lighter current in the primary circuit, while the larger armature will be attracted when the magnet 18 is energized from the heavy current in the secondary circuit. The movement of the small armature will cause the locking member 51 to move backwardly, as above described, and the contactor is so designed that the contact arm 30 will move onto the contact 34, thus closing the secondary circuit just when the locking member 51 has been thrown backwardly to unlock the main armature 46. The magnet 18 thus receives its heavy current impulse when the armature 46 is unlocked so that said armature will be moved upwardly, and in so doing will step the wheel 15 forward one step. For this purpose, said main armature 46 has a finger 222 pivoted thereto which co-operates with the teeth 223 of the wheel 15 to move said wheel forward when the armature is raised. The wheel 15 is prevented from overrunning partly by the spring-pressed roll 224 and partly by the co-operation of the finger 222 with the stop 225. The roll 224 holds the wheel from backward movement and the finger 222 is pivoted to the armature so as to permit it to click over the teeth 223 when the armature 46 drops. When the armature 46 has been raised, it will be automatically locked by the gravity lock 54 which is controlled by an unlocking magnet 55.

As stated above, the magnet 18 is so constructed that it will be operative only when it is energized first by a comparatively light current and then immediately thereafter by a comparatively heavy current. If more than the prescribed time interval elapses between the light and the heavy current impulses, the lock 51 will have time to swing back into locking position before the heavy current and thus the armature will not be operated.

The contactor 24 is so constructed that the contact arm 30 will move upwardly across the contacts 33, 34 at the same speed, regardless of the speed of the car, all as described in my co-pending application. Se. No. 61,493, and, therefore, the magnet 18 will receive the relatively-light and then relatively-heavy current in the proper time interval regardless of the speed of the trolley car.

The magnet 18 is so constructed that it will not respond when it receives a relatively-heavy current only without the preliminary relatively-light current immediately preceding it. This is so because the relatively-small armature 45 will be satu-

rated when the magnet is subjected to the relatively-light charge and hence when the relatively-heavy current is used without the preceding relatively-light current, a sufficient proportion of the magnet flux passes around through the lock 51 and tail of the armature 46 to hold these parts together with sufficient force to prevent the lock from being thrown back by the auxiliary armature 45 and said auxiliary armature, therefore, will not be effective to operate the lock 51 and unlock the main armature.

Having referred briefly to the manner in which the signal operates, I will now refer more in detail to the various circuits which are illustrated for giving the signal indication.

57 is a feed wire connected to the trolley at each end of the block. This feed wire has connected thereto a resistance 56 which is connected by a wire 60 to contacts 61 that are closed by an insulated portion of the contact lever 23 when the latter is in its normal position, one of said contacts being connected to the ground at 62, these connections constituting at each end of the block 90 a normally-closed local circuit. The signal wire 8 is connected at each end to the resistance 56 intermediate of its length, as shown at 86, said signal wire 8 having therein at each end a relay 560 which controls a plurality of armatures 347, 75 and 148. The circuit connections for the signal wire 8 are such that under normal conditions the potentials at the two points 86 are the same and, therefore, no current will be flowing normally in the signal wire and the two relays 560 therein will be de-energized. The feed 57 also has a wire 63 connected thereto which leads to a pair of contacts 64 which are bridged by an insulated portion 105 of the contact lever 23 when the latter is in its normal elevated position shown in Fig. 1, said contacts being connected by a wire 65 to a current regulator magnet 58, said latter magnet being connected to the ground 110 by a wire 59 having a suitable resistance therein. The feed 57 also has connected thereto the circuits by which the lamps in signals 10 and 11 are operated. The circuit which includes the red lamp 14 is as follows:

The resistance 67 which is connected to the wire 63 and forms part of the current regulator, wire 68, contacts 69 which are bridged by the armature 75 of the magnet 120 560 when the latter is de-energized, wire 70, contacts 71 that are normally bridged by armature 76 of the magnet 72 when the latter is de-energized, wire 73, contacts 74 which are bridged by the armature 77 of the 125 magnet 18 when the latter is de-energized, wire 78 which leads to the yellow lamp 79 of a two-lamp signal 80, wire 81, contacts

- 82 which are closed by the armature 83 of the magnet 18 when the latter is deenergized, wire 84 to the red light 14 of the signal 10 and thence to ground.
- 5 When there is no car in the block the signals will be displayed as seen in Fig. 4, and all the relays will be deenergized. When a car proceeding to the right actuates the contactor 24, the magnet 18 will be energized, as above described, thereby to step the signal-setting wheel 15 forward one step, the armatures controlled by said magnet 18 will be raised, and the contact lever 23 will be moved into its intermediate position, as 10 above described. These operations result in changing the circuits to the signals 10 and 80 so as to cause the green lamp 12 to be lighted in signal 10 and the red lamp 85 to be lighted in signal 80, as seen in Fig. 5.
- 20 When the signal-setting wheel 15 is stepped forward and the contact member 23 is moved downward into its intermediate position, the contacts 61 and 64 are opened. At the same time the end of the contact 23 engages the 25 cam projection 87 on a light-changing contact member 88, thereby forcing the contact to the right and closing the pairs of contacts 89, 90 and 91. The closing of the contacts 89 closes a shunt circuit 92 which has a small 30 resistance 93 therein and is connected to the signal wire at 86, this shunt circuit being grounded at 62. The closing of this shunt circuit will cut out some of the resistance 56 so that the potential at the point 86 at the 35 left-hand end of the block will be less than that at the right-hand end of the block, and consequently a current will flow from the feed wire 5 at the right-hand end of the block, through the signal wire 8 and shunt 40 circuit 92 to the ground at the left-hand end of the block. This results in energizing the relays 560 in the signal wire, thereby causing their armatures to be raised.

The closing of the contacts 91 closes a circuit through the relay 72, thus causing it to be energized to raise its armatures. This circuit thus closed through the relay 72 is as follows:

Wire 95, connected to the wire 63, contacts 91, wire 96 connected to the relay 72 and leading to the wire 65 which is connected to the ground through the regulating magnet 58.

Hence when the contactor has been actuated the magnets 18, 72 at the entering end of the block and both magnets 560 are energized, as seen in Fig. 5. The energizing of the relays 560 and 72 at the right-hand end of the block and the locking of the signal-setting magnet 18 in its elevated position when the latter is energized changes the circuits so as to cause the green lamp 12 to be lighted in signal 10 and the red lamp 85 to be lighted in signal 80 when one car only

has entered the block and the contact member 23 is in its intermediate position. The circuits which operate the lights may be traced as follows:

Wire 57, wire 63, resistance 67, wire 68, contacts 190 which are now closed by the 70 raised armature 75 of the relay 560, wire 94, contacts 98 which are now closed by the raised armature 99 of the relay 72, wire 100, contacts 101, which are now closed by the raised armature 83 of the magnet 18, wire 75 102 which leads to the red light 85 in the signal 80, wire 81, contacts 103 which are now bridged by the raised armature 104 of the magnet 18, wire 105, contacts 90 which are closed by the contact member 88, wire 80 106, to the green light 12 in signal 10 and thence to ground.

At the opposite end of the block, the only change is that the relay 560 has been energized thereby raising its armature, the relay 72 and the signal-setting magnet 18 remaining deenergized. The raised armature 75 of the relay 560 opens the circuit leading to the yellow lamp 79 of the signal 80 at the right-hand end of the block and closes the 90 circuit leading to the red lamp 85 at the said end of the block, the circuit through the lamps being as follows:

Wire 57, wire 63, resistance 67, wire 68, contacts 190 which are closed by the raised 95 armature 75, wire 94, contacts 107 which are closed by the lowered armature 99, wire 108, contacts 109 that are closed by the lowered armature 110 of the magnet 18, wire 102 to the red lamp 85 at signal 80, wire 81, contacts 82 which are closed by the armature 83 of the magnet 18, wire 84 to the red lamp 14 and thence to ground.

Both signals at the right-hand end of the block will thus show red, and at the left-hand end of the block, the signal 80 will show red while the signal 10 will show green, as seen in Fig. 5. This indicates to the motorman that he has been properly counted into the block. As the car entering the 110 block passes the contactor 28, the locking magnet 55 is energized, thereby to release the lock 54 and allow the armatures of the signal-setting magnet 18 to drop. The dropping of the armature of the signal-setting magnet 18 changes the circuits in the lamps of the signals 10 and 80 so as to display a yellow lamp 79 at 80 and a red lamp 14 at 10, as seen in Fig. 6, thus placing the system in condition for a second car to follow 120 the first car into the block. The circuits by which the operation of the contactor 28 results in energizing the locking magnet 55 are as follows:

The contactor 28 has the same construction as the contactor 24, that is, it is provided with a vertically-swinging contact lever 111 adapted to engage two contacts 112

and 113 successively as the lever is raised, said lever being given its vertical upward movement by a trolley wheel passing thereunder. The contact 112 is connected by a 5 wire 114 to contacts 115 which are closed by the armature 116 of the magnet 18 when the latter is deenergized, said contacts being connected by a wire 119 having a resistance 120 therein to a magnet 121, the latter being 10 connected by wire 122 to the ground. The contact 113 is connected by a wire 123 to the resistance 120. When the contact lever 111 moves upwardly it first engages contact 112, but this does not result in closing any 15 circuit because the armatures of the magnet 18 are raised and the contacts 115 are opened. As the contact member 111 strikes the contact 113, however, a current will be sent through wire 123 to the lock-releasing 20 magnet 55, and thence to the ground through the wire 124, a portion of resistance 120, magnet 121, wire 122 and contacts 136 which are closed by the main armature 137 of magnet 121. The lock-releasing magnet 55 is 25 thus energized and the armature 40 is released, so that all of the armatures of the magnet 18 will fall. When these armatures drop into their lowered position, the contacts 74 and 82 are closed thereby restoring 30 the circuits to the signals 10 and 80 to their initial condition so that the yellow lamp 79 of the signal 80 will be lighted and the red lamp 14 of signal 10 will be lighted.

The magnet 121 is similar in construction 35 to the magnet 18 in that it has the auxiliary and main armatures 138 and 137, and the locking member 238 for normally locking the main armature from movement, and in that it is necessary to energize it by first a 40 comparatively-light and then immediately thereafter by a comparatively-heavy current in order to operate the main armature. Consequently when said magnet is energized by closing the circuit through contact 113 and 45 receives a heavy charge, it will not operate the armature 137 and the contacts 136 will, therefore, remain closed.

If now a second car enters the block while it is still occupied by the first car, the signal-setting magnet 18 will be energized, as above 50 described, by the operation of the contactor 24, thereby stepping the signal-setting wheel 15 forward a second step and placing the contact lever 23 in its lowered position. 55 The energizing of the contact 18 and the consequent raising of its armatures, together with the placing of the arm 23 in its lowered position results in changing circuits to the signals 10 and 80 so that a yellow light 13 60 will be exhibited at the signal 10 and a red light at signal 80, as seen in Fig. 7. The motorman, therefore, receives indication that his car has been properly counted into the block and also receives indication that there

is a car ahead of him in the block by the 65 fact that the yellow light 13 of the signal 10 is lighted instead of the green light 12. This result is secured by the opening of the contacts 90 and the closing of the contacts 126 by the contact lever 23 in its lowered position. The cam projection 87 on the contact lever 88 is so constructed that when the contact lever 23 is in its lowered position the contact lever 83 is allowed to move to the left 70 slightly, but not sufficiently to open the contacts 91 and 89. The contacts 90 are located slightly back of the contacts 89 and 91 so that in this intermediate position of the contact lever 88 the contacts 90 are open, while the contacts 89 and 91 remain closed. With 75 the contacts 90 open and the contacts 126 closed and with the signal-setting magnet 18 energized and its armatures raised, the circuits to the lights in the signals 10 and 80 will be as follows:

Feed wire 57, wire 63, resistance 67, wire 68, contacts 190, wire 94, contacts 98, wire 100, contacts 101, wire 102, red light 85, wire 81, contacts 103, wire 105, wire 127, contacts 126, wire 128 to the yellow light 13 90 in signal 10 and thence to ground. The change from the green light 12 of signal 10 which indicates "proceed" to the yellow light 13 of said signal 10 which indicates "proceed with caution" is secured by the 95 fact that when a second car enters the block which is already occupied by another car, the counting-in device will place the contact lever 23 in its lowest position and thus hold the light-changing contact 83 in its intermediate position, in which position it closes the circuit to the yellow lamp 13 instead of to the green lamp 12. It will be noted that the green lamp 12 will be lighted only when the light-changing contact member 88 is in 100 its farthest position to the right, and this only occurs when the contact member 23 is in its intermediate position. The only time when the contact 23 will be in its intermediate position will be when the counting-in 105 wheel 15 has been stepped forward one step only, and this only occurs when a car seeks to enter an empty block. If a second car seeks to enter the block already occupied by another car then the counting-in wheel 15 110 will be moved forward a second step which will result in so placing the contact members 23 and 83 as to cause the circuits to the yellow light 13 to be closed, this being accomplished by the roll 21 moving off from the 115 second step of the cam 20 onto the face of the wheel 15.

When a car enters the block it is necessary that it should actuate both the contactors 24 and 28 in order to place the signal 125 in condition for the second car to enter the block. The operation of the contactor 24 sets the signal and displays the red light in sig-

nal 80, and the green or the yellow light in signal 10, and also causes the red lights to be displayed in both signals 10 and 80 at the opposite end of the block. The actuation 5 of the contactor 28 unlocks the armatures of the signal-setting magnet 18 so as to restore the lights in signals 10 and 80 to their normal condition without disturbing the signals at the opposite end of the block.

10 When a car leaves the block, it is necessary that it should actuate the contactors 29 and 26 successively in order to restore the signal to its initial position. The actuation of the contactor 29 closes a circuit connecting the restoring circuit 9 with the contactor 26 so that when the contactor 26 is actuated a restoring impulse will be sent over the restoring circuit through the signal-restoring magnet 19 at the entering end of 15 the block thereby actuating the latter to step the signal-restoring wheel 17 forward one step. This signal-restoring magnet 19 is constructed similarly to the signal-setting magnet 18, that is, it is so designed that 20 it will only be operated by first a light and then a heavy current, and the contactor 26 is designed to close in proper sequence the circuits by which the light and heavy currents are delivered to the restoring magnet 25 19. Both contactors 29 and 26 are similar to that above described, the contactor 29 having a vertically-moving contact member 130 adapted to engage two contacts 131 and 132 in succession as it is moved upwardly by 30 a passing trolley, and the contactor 26 being provided with the vertically-moving contact member 133 adapted to engage two contacts 134 and 135 in rapid sequence when said member is moved upwardly by a passing 35 trolley. Both of the contacts 131 and 132 of the contactor 29 are connected to the relay 121 by connections similar to that described with reference to the contactor 28 and the relay 121 at the left-hand end of 40 the block. When, therefore, the contactor 29 is actuated there will first be a circuit established through contact 131, wire 114, at the right-hand end of the block, contacts 115 which are closed by the armature 116, wire 119, resistance 120 to the relay 121, thence by wire 122 to contacts 136 which are closed by the heavy armature 137 of the relay 121 and thence to ground. This circuit includes all of the resistance 120 which will 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940

will be delivered to the relay 121 which will be sufficient to raise the armature 137 and this heavy current will be sent through the relay immediately after the light current and just when the small armature 138 has thrown the locking member 238 backwardly out of operative position. The heavy armature 137 is thus raised thereby opening the contacts 136 and closing contacts 139. The armature becomes automatically locked in this position by a gravity lock 140 which is controlled by a lock-releasing magnet 43. The armature 137 is shown as provided with a spring contact 271 which engages the contacts 136 when said armature is down. This spring contact is normally locked against the contacts 136 by means of a locking pawl 272 which has a cam projection thereon situated to be engaged by the end of the armature 137 when the latter is raised. As a result, when the armature 137 is unlocked and lifted, as above described, the contact 271 will maintain the parts 136 closed until said armature reaches the upper limit of its movement, at which time the locking pawl 272 is released from the contact 271, thus opening the contacts 136, this occurring at the time that the contacts 139 are closed. This closing of the contacts 139 by the operation of the contactor 29 closes circuit connections between the contactor 26 and the restoring circuit so that when the trolley passes contactor 26 first a light and then a heavy current will be sent over the restoring line wire 9 to the signal-restoring magnet 19 at the entering end of the block, thus restoring the signal. When the contact 133 of the contactor 26 is moved upwardly and engages the contact 134, a circuit will be formed including contact 134, wire 35, a portion of resistance 36, wire 144, to contacts 139, wire 145, wire 146 to contacts 147 which are now bridged by the armature 148 of the relay 560, restoring line wire 9 to contacts 147 at the entering end of the block which are also closed by the armature 148, wire 146 to restoring magnet 19, wire 150 from the restoring magnet to the ground through contacts 151 which are closed by the armature 250 of the energized relay 72. The circuit above outlined has most of the resistance 36 therein and will send through the restoring relay at the entering end of the block a current which is sufficient to raise the small armature 251 thereof, but is insufficient to raise the large armature 152. When the contact 133 engages the contact 135, a circuit will be established which will send a heavy current through the restoring magnet 19 at the entering end of the block which is sufficient to raise the large armature 152, and this occurs just when the armature is unlocked by the action of the small armature in throwing the locking member 153

backwardly. This circuit for the heavy current comprises contact 135, wire 42, lock-releasing magnet 43, wire 44 to the resistance 36, a portion only of said resistance, 5 wire 144, contacts 139, wire 145, wire 146, contacts 147, and restoring line wire 9 to the restoring relay magnet 19 at the left end of the block, as above described. This circuit leading from the contact 135 contains less of 10 the resistance 36 than the circuit leading from the contact 134, and thus when the circuit is closed through the contact 135 a heavier current is sent over the restoring line wire than when the circuit is closed through 15 the contact 134. When the restoring magnet 19 is thus energized, the counting-out wheel 17 is moved forward one step, and this operation will occur for each car that leaves the block. The closing of the above- 20 mentioned circuit through the lock-releasing magnet 43 energizes the latter and unlocks the armature 137, allowing it to fall into its normal position.

When all the cars have left the block the 25 signal will be restored to its initial condition.

In the above description, I have referred to cars entering the block from the left, Fig. 1, but this description will apply equally 30 well to cars entering from the right.

My signal system is so arranged that it will operate in the same manner whether the car enters the block over one or the other of the branch tracks of the turn-out. In other 35 words, a car entering the block along the trolley 5 will actuate the signal system in just the same way that a car entering a block along the trolley 4 will. Similarly, a car leaving a block along the trolley 6 restores 40 the signal in just the same way that a car leaving the block along the trolley 7 does. I accomplish this result by connecting the contactors 24 and 25 at the branch 2 in parallel, and also connecting the contactors 26 45 and 27 at the branch 3 in parallel. The contactor 25 has the swinging contact member 300 adapted to engage the two contacts 338 and 340, respectively, and the contact 338 is connected to the contact 33 by the wire 212, 50 and the contact 340 is connected to the contact 34 by the wire 213. Similarly, the two contacts 331 and 332 of the contactor 27 are connected to the contacts 134 and 135 of the contactor 26. By thus connecting these contactors in parallel, it makes no difference 55 which branch of the turn-out the trolley is on.

In block signal systems of the counting-in and counting-out variety, it is desirable to 60 provide means whereby after a predetermined number of cars have entered the block and are occupying the block, the counting-in device shall be rendered inoperative, so that no additional cars can be counted into the 65 block, while it is still occupied by this pre-

determined number. In the block signal system herein illustrated, I accomplish this end by providing means whereby the counting into the block of the last car of the predetermined number will open the circuit 70 controlling the signal-setting magnet 18 and will hold said circuit open so long as the predetermined number of cars are in the block. This makes it impossible for any additional cars to be counted into the block 75 while the predetermined number of cars are occupying the block. This is accomplished by means of the contact pawl 38. As each car is counted into the block the counting-in wheel 15 is advanced one step relative to the 80 counting-out wheel 17, and when the predetermined number of cars have entered the block, the counting-in wheel 15 will be rotated to such a position that the tail 161 of the contact pawl 38 will be engaged by the 85 roll 21 thereby rocking said pawl about its pivot and lifting it from the contact 162. This opens the circuit of the magnet 18. The contact pawl will remain in this position so long as the predetermined number 90 of cars remain in the block, but when one of the cars has been counted out of the block, the forward movement of the counting-out wheel 17 will remove the roll 21 from the tail 161 of the pawl 38, thus allowing the pawl to drop back onto the contact 162, thereby reestablishing the circuit through the signal-setting magnet 18.

I have also provided means whereby when the last one of the predetermined number of 100 cars has entered the block, both the signals 80 and the signals 10 and 11 will all give a "stop" indication. It will be remembered that normally whenever the block is occupied by a car or any number of cars less than 105 the predetermined number, the signal 80 at the entering end of the block gives a yellow light or a "proceed with caution" indication, while the other signals at the entering end of the block give a red or "stop" indication. 110 The yellow or "proceed with caution" indication of the signal 80 at the entering end of the block indicates to a car that it may proceed into the block cautiously, although the block is occupied by one or more cars 115 proceeding in the same direction. When the last car of the predetermined number of cars enters the block, all of the signals display the red light, thus giving the "stop" indication, which indicates that no car is to enter 120 the block from either end. I accomplish this herein by the following means:

The shaft 16 of the counting-in and counting-out device has slidably mounted thereon a disk 171 which is provided with 125 a finger 172 extending through the counting-in wheel 15 adjacent the tail 161 of the contact pawl 38 so that when the last car of the predetermined number has entered the block, the roll 21 will not only engage 130

the tail 161 of the contact pawl 38, but will also engage the beveled end of the finger 172, thus moving the plate 171 longitudinally of the shaft 16. When this plate 5 is thus moved longitudinally, it engages a pivoted contact member 173 which is insulated from said plate and which normally closes contacts 174 in the wire 78 leading to the yellow lamp 79 of the signal 80 and 10 moves said contact member against the contacts 175 thereby closing a shunt circuit 176 which connects at one end with the feed through the wire 68 and at the other end connects with the wire 102 leading to 15 the red light 85 of signal 80. The opening of the contacts 174 in the circuit of the yellow lamp 79 and the closing of the contacts 175 cuts the yellow lamp 79 out and causes the red lamp 85 to be lighted. When 20 this condition exists all of the signals will show the red light or "stop" indication and they will maintain such indication so long as the predetermined number of cars remain in the block. As soon as one of the cars 25 passes out from the block at either end the consequent forward movement of the signal-restoring wheel 17 will carry the roll 21 off from the pin 172 thereby allowing the contact member 173 to resume its normal position 30 in engagement with the contacts 174. This will cause the yellow lamp 79 of the signal 80 at the entering end of the block to be lighted and the red lamp 85 to be extinguished, thus indicating to a car approaching 35 from the left end that it is permissible for it to enter the block. So long as the signals give the red or "stop" indication it is not permissible for any car to enter the block from either end.

40 It sometimes happens that when a block is occupied by a car proceeding in one direction therethrough that another car approaches said block from the opposite direction, and it is desirable that the second 45 car should proceed into the block over one branch of the turn-out past the signals which are set against it, and then should leave from the same end of the block over the other branch of the turn-out before the 50 first-mentioned car has left the block. For instance, if the block were half a mile or so long and the first-mentioned car had just entered the block, the second car which did not desire to go through the block but 55 merely desired to pass around the turn-out at the end of the block, could save considerable time by proceeding into the block past the signal set against it by the first car and then turn around the turn-out and pass 60 out of the block from the same end without waiting for the first car.

My signal device is so constructed that when a car proceeds into a block while the signals 80 and 10 or 11 are both showing red, 65 thus indicating that the block is occupied

by another car proceeding in the opposite direction, said car will be counted into the block, and when the car passes out of the block from the same end over the other branch of the turn-out, it will be counted 70 out of the block again, thus restoring the signal to the same condition that it was before said car entered the block. It will be remembered that when a car passes into an empty block or one which is occupied by 75 a car going in the same direction, the signal 10 or 11 will change from the red to the green or the yellow indication when said car is counted into the block. Under the conditions above stated, however, where a 80 car enters the block in defiance of signals 80 and 10 or 11 set against it, the counting of the car into the block will cause a green or a yellow indication at the signal 10 or 11 in addition to the red indication, thus 85 indicating to the car that it has been counted into the block, but also indicating that the block is occupied by a car coming in the opposite direction. When, therefore, the signal 80 at either end of the block is overrun and 90 a car is counted into the block, this indication will be given at the signal 10 or 11 without, however, eliminating the "stop" indication of said signal. Moreover, my signal is so constructed that if a car does 95 thus purposely overrun the signal 80 for the purpose of passing around the turn-out and in doing so accidentally fails to be registered into the block because of improper operation of the contactor or from any 100 other cause, then when said car backs out of the block, it will also fail to be counted out of the block so that the signal system will be left in a safe condition. These results are secured as follows:

When a car has entered the block from the right-hand end both of the relays or magnets 560 are energized. When a car coming from the left passes the contactor 24, the signal-setting magnet 18 at the left-hand end of the block will be energized, as above described, thus stepping the signal-setting wheel forward one step. This will bring the contact lever 23 into its intermediate position and the light-changing contact 88 into its extreme position to the right so as to close all three pairs of contacts 89, 90 and 91. This operation results in opening the circuit 115 60 and closing the branch circuit 92, and as a result the signal-setting line circuit 8 will 120 be restored to its initial condition, in which the potential at the points 86 at each end are the same. This will cause the deenergization of both relays 560, thus allowing their armatures to fall. The closing of the contacts 91 will close the circuit through the relay 72 at the left-hand end of the block, thus causing it to lift its armatures, and the closing of the contacts 90 will close the circuit through the green light 12 of the signal 10, 130

as seen in Fig. 9. Under these conditions, both the red lamp 14 and the green lamp 12 of signal 10 will be lighted. The circuit of the green lamp will be feed wire 57, wire 63, 5 resistance 67, wire 68, contacts 69 which are now closed by the armature 75 of the de-energized relay 560, wire 70, contacts 174 which are now closed by the elevated armature 76 of the relay 72, wire 175 to the wire 102 which leads to the red lamp 85 of signal 80, wire 81, contacts 103 which are now closed by the raised armature 104, wire 105, contacts 90, wire 106 to the green light 12 of signal 10 and thence to the ground. The red 15 light 14 is maintained burning through the following circuit:

Feed wire 57, wire 63, resistance 67, wire 176, contacts 177 which are now closed by the lowered armature 148, wire 178, contacts 20 179 which are closed by the raised armature 180 of the signal-setting magnet 18, and wire 84 to the red light 14.

As the car which has passed the signal 80 moves forward onto the single track and 25 passes the contactor 28 going to the right, the operation of said contactor will energize the unlocking magnet 55, thus unlocking the armatures of the signal-setting magnet 18 (see Fig. 10). When this car starts to back 30 out of the block and again actuates the contactor 28, the magnet 121 will be energized, thus establishing the circuit to the signal-restoring magnet 19 so that when the car backs out over the branch trolley 5 and actuates the contactor 25, it will be properly 35 counted out from the block. When the contactor 28 is actuated by the car moving to the right, the engagement of the contact arm 111 thereof with the contact 112 has no result 40 because the circuit connected to said contact 112 is open at the contacts 115. When the contact arm of the contactor 28 engages the contact 113, however, a circuit will be closed through wire 128, unlocking 45 magnet 55, wire 124, magnet 121, wire 122, contacts 136 to the ground, and as this circuit includes only a part of the resistance 120 it will be a heavy circuit. The current of this circuit will actuate the unlocking 50 magnet 55, but will not actuate the heavy armature 137 of the magnet 121 because when the magnet 121 is energized with the relatively-heavy current at the time that both armatures are down, the magnet attraction between the tail of the heavy armature 137 and 55 the lock 238 is sufficient to prevent the auxiliary armature 138 from actuating the lock and thus unlocking the main armature, this being due to the fact that the small armature 60 is saturated by a relatively-light current.

The result of the car moving under the contactor 28 to the right, therefore, is merely to unlock the armatures of the signal-setting 65 magnet 18. When the car moves over the

contactor 28 in backing out of the block, the engagement of the contact arm 111 with the contact 112 will close the circuit through the magnet 121 carrying a light current, thereby attracting the armature 138, and immediately thereafter the circuit will be closed through the contact 113 which will deliver a heavy current to said magnet, thus raising the main armature 137. The first circuit leading from the contact 112 comprises the 70 wire 114, contacts 115 which are now closed by the lowered armature 116 of the signal-setting magnet 18, wire 119, resistance 120, magnet 121, wire 122, contacts 136 to the ground. This circuit includes all of the resistance 75 120. The engagement of the contact arm 111 of the contactor 28 with the contact 113 closes the secondary circuit through the magnet 121 comprising the wire 123, magnet 55, wire 124 and a part only of the resistance 80 120, magnet 121, wire 122 and contacts 136. This results in raising the magnet armature 85 137 to close the contacts 139, said armature becoming locked automatically by the gravity lock 140. As the car backs off under the contactor 25, it will close first a primary and then a secondary circuit through the counting-out magnet 19, thereby to count the car 90 out of the block. The primary circuit by which the magnet 19 is energized with the 95 light current consists of the contact 338, wire 212, wire 35, part of resistance 36, wire 144, contacts 139 which are now closed by the raised armature 137, wire 145, the counting-out magnet 19, wire 150 to the ground 100 through the contacts 151 which are closed by the raised armature 250 of the relay or magnet 72. This circuit provides the light current impulse for the magnet 19 which is sufficient to raise the auxiliary armature 251, 105 thus unlocking the main armature 152. The secondary circuit is through the contact 340, wire 213, wire 42, unlocking magnet 43, wire 44, through a portion only of the resistance 36, wire 144, contacts 139, wire 145, magnet 110 19, wire 150 to the ground through the contacts 151. The counting-out magnet 19 will 115 thus be properly energized and the car will be counted out of the block, thus leaving the signals in the same condition that they were before the signal 80 was overrun.

If there are two cars which overrun the signal 80 in succession, then the same results will follow except that the second car which overruns the signal 80 before the first car 120 has backed out of the block will get both a red and a yellow light at the signal 10 instead of a red and a green light. This is accomplished because when the second car passes the contactor 24 the signal-setting 125 magnet 18 will be stepped forward a second step, thus carrying the contact arm 23 into its lowered position, closing the contacts 126 and allowing the light-changing contact 88 to swing into its intermediate pos- 130

tion which will open the contacts 90. The result of this change is to close the circuit to the yellow lamp 13 instead of to the green lamp 12, as above described and as seen in Fig. 11.

- As stated above, my signal system is so constructed that if a car overrunning the signal 80 at either end of the block should accidentally fail to actuate the contactor 10 and thereby be registered into the block, said car in backing out of the block over said contactor will not operate the counting-out mechanism to count a car out of the block. If it be assumed that a car has entered the block from the left-hand end, then all the magnets at the right-hand end of the block will be deenergized except the magnet 560, as shown at the right-hand end of Fig. 6. If now a second car accidentally overruns the signal 80 at the right-hand end of the block, but in doing so fails to operate the contactor 27, then, of course, no change will occur in the various magnets at the right-hand end of the block and they will all still be deenergized except the magnet 560. Now if said second car backs out of the block under the contactor 27 and in doing so actuates said contactor, the counting-out mechanism will not be operated, so that there is no possibility that in backing out of the block the second car will count the first car out of the block. When said second car does thus back out of the block and the swinging arm of the contactor engages the contact 331, no circuit can be established through the counting-out magnet 19 because the ground connection 150 for said magnet is open at the contacts 151. A circuit, however, will be established through wire 35, resistance 36, and wire 37 and counting-in magnet 18, which circuit contains all of the resistance 36 and thus energizes said magnet 18 with a light current. A second circuit will immediately be established through contact 332, wire 42, unlocking magnet 43, wire 44, a part of resistance 36, wire 37 to the counting-in magnet 18. Said counting-in magnet will, therefore, be energized to count the car into the block. While, of course, this does not accurately indicate what has transpired, yet it is an error on the safe side because it would be dangerous to count a car out of the block while said car was still in the block.
- My signal system is also so constructed that if a car accidentally overruns a signal 80, as above described, and in doing so becomes counted into the block and then backs out of the block without actuating the contactor 28 or 29, said car will be counted out of the block. If it be assumed that a car has entered the block from the left-hand end, then all the magnets at the right-hand end of the block will be deenergized except the magnet 560, as shown at the right-hand end,

Fig. 6. If now a second car accidentally overruns the signal 80 at the right-hand end of the block and actuates the contactor 27, then the signal-setting magnet 18 will be energized thereby stepping the counting-in 70 wheel 15 forward and counting the car into the block, as above described. This operation results in deenergizing the magnet 560 at the right-hand end of the block and closing the circuit through the magnet 72 so 75 that the armatures for the magnets 18 and 72 will be raised while those for the magnet 560 will be down. When now said car backs out of the block and operates the contactor 27, a preliminary circuit will be established 80 through contact 331, wire 35, part of resistance 36, wire 144, to contacts 341, which are now closed by the raised armature 77 of magnet 18, wire 342 to contacts 343 which are now closed by the raised armature 344 85 of the magnet 72, wire 345 to contacts 346 which are now closed by the lowered armature 347 of magnet 560, wire 348, wire 146 to the counting out magnet 19, wires 150 to ground, the contacts 151 therein being 90 closed by the raised armature 250. The closing of this circuit will energize the counting-out of magnet 19 with a relatively-light charge. As soon as the contact arm of contactor 27 engages the upper contact 332, a secondary circuit will be established through said contact wire 42, lock-releasing magnet 43, wire 44, portion of resistance 36, wire 144, contacts 341, wire 342, contacts 343, wire 345, contacts 346, wire 348, wire 146 to 100 the signal-restoring magnet 19 and thence to ground. This secondary circuit has less of the resistance 36 therein than the preliminary circuit, and said magnet will be, therefore, energized with a heavy current, thus 105 causing it to be operated to count the car out of the block. The counting of the car out of the block will restore the contact lever 23 to its upper position, thus opening the circuit of the magnet 72 so that the armatures 110 thereof will fall, and also reestablishing circuit conditions by which the magnet 560 is energized. The restoring of the contact arm 23 to its upper position will close the circuit through the lock-releasing magnet 115 55, thereby energizing the latter and unlocking the armature 46 of the signal-setting magnet. This circuit is as follows: Feed 57, wire 63, wire 411, contacts 412 which are now closed by the raised contact lever 23, 120 wire 413, contacts 414 which are now closed by the raised armature 116 of the magnet 18, lock-releasing magnet 55, wire 124, through a portion only of the resistance 120 to the magnet 121 and thence to the ground 125 through the contacts 136. As this circuit includes only a part of the resistance 120 the magnet 121 will be energized with a heavy current and will, therefore, not be responsive, but the lock-releasing magnet will be 130

energized to unlock the armature 46 of the signal-setting magnet 18, thus restoring the signal system to the condition it was in before the car overran the signal 80.

- 5 My improved signal is also so constructed that if two cars start to enter the block simultaneously at opposite ends and the two contactors 24 and 27 are simultaneously actuated, both cars will get a red or "stop" 10 indication at the signal 10 and if either car backs out of the block the other car will immediately get a "proceed" signal.

It will be further noted that the signals are properly set only when one of the 15 contactors on the branch trolley and the adjacent contactor on the main trolley are actuated in succession. It will be seen that in order to set the signal it is necessary to operate both a contactor on the branch trolley 20 and the adjacent contactor on the main trolley, and also to actuate the contactor on the branch trolley first. It will also be seen that in order to restore the signal it is necessary that both of these contactors should be actuated but that the contactor on the main 25 trolley should be actuated first. In other words in order to set the signal by a car entering from the left-hand end of the block it is necessary to actuate the contactor 24 or 25 first and subsequently to actuate the contactor 28, while to restore the signal from said end of the block it is necessary to actuate the contactor 28 first and then to actuate either the contactor 24 or 25. My 30 signal device, therefore, comprises two contactors at each end of the block, each of which closes two circuits in succession when it is actuated, but which are so connected to the signal system that the contactors must 35 be operated in one sequence in order to set the signal and in the reverse sequence in order to restore the signal. In other words, the contactors which are shown in my signal device are arranged to close and open one 40 circuit and then close another circuit within a predetermined time interval, and the signal mechanism is so constructed that unless one circuit after being closed is broken and the other circuit closed within the predeter- 45 mined time interval, the device will not operate. In Fig. 13 I have shown a little different construction adapted for actuating the signal-setting or signal-restoring magnets, but which requires that a circuit should 50 be broken and another circuit closed in immediate sequence in order to operate the device. In this figure, I have shown the counting-in wheel 15 which is actuated by the pawl 450. This pawl constitutes the 55 armature of a signal-setting magnet 451 which is connected to the ground at 452 and which is also connected by a wire 453 to the upper contact 455 of a contactor, such as above described. The lower contact 456 of 60 this contactor connects by wire 457 to a con-

trolling magnet 458 which is also connected to the ground. This controlling magnet 458 has an armature 459 provided with a locking finger 460 which is adapted to move from the full line position Fig. 13 to the 70 dotted line position. When the magnet 458 is energized, the locking finger 460 will be in the full line position, but when the magnet 458 is deenergized, said finger will be swung into the dotted line position under 75 the influence of the spring 461. The pawl 450 is provided with two stop projections 462 and 463 that are situated beneath the end of the locking finger 460 when it occupies either the full or the dotted line position. Said pawl 450 is provided intermediate of these projections with a depressed portion 464. The contact is so constructed that normally the swinging arm 465 of the contactor will have engagement with the 80 contact 456 so that under normal conditions the magnet 458 is energized and the locking arm 460 will be held in its full line position. As a car passes under the contactor, the swinging arm 465 is moved upwardly thereby breaking the circuit of the magnet 458 and immediately thereafter engaging the contact 455, thus completing the circuit through the magnet 451. As soon as the circuit 457 is broken, the magnet 458 will 85 be deenergized and the locking finger 460 will swing from its full toward its dotted line position, but before the finger can complete its swinging movement the circuit 453 leading to magnet 451 is closed at contact 100 455 so that said magnet will be energized, thus moving the pawl 450 upwardly. This movement is permitted only while the locking arm 460 is in its intermediate position over the depressed portion 464, and, therefore, the signal-setting magnet cannot be 105 operated except when the circuit 457 is broken and the circuit 453 is closed immediately thereafter and within a predetermined time interval. While this mechanism 110 is slightly different from that illustrated in Figs. 1 and 2, yet it accomplishes the same object.

In order that the signal may properly operate it is essential that when the block is 115 unoccupied, the potential at the points 86 at each end of the block should be the same so that both magnets 560 will be deenergized. Sometimes the traffic conditions are such that the voltage at one end of the block will be less than at the other, and if this difference is a sufficient amount, it might happen that a current would be established from one end to the other of the block through the signal-setting wire, thus energizing the 125 magnets 560 even though no car was in the block. To prevent this from happening I employ a current regulator at each end of the block for automatically varying the resistance of the feed 57 at said end of the 130

block. These current regulators each comprise a solenoid 58, the core of which carries a contact 501 that is adapted to engage a plurality of contacts 502, 503 and 504 that are connected to different points of the resistance 56. The contact 501 is connected by a wire 505 to the feed end of the resistance. These current-regulating solenoids or magnets 58 are in the normally-closed local circuit leading from the trolley to the ground through the contacts 69 and are, therefore, normally energized when the block is unoccupied. When the voltage is normal the cores of the magnet will be held in their elevated position, but if the voltage at either end of the block drops for any reason, the core of the corresponding solenoid will drop into contact with one or another of the contacts 502, 503, 504, depending upon the degree of drop in the voltage. As the contact 501 comes into engagement with the contacts 502, 503, 504, more or less of the resistance 56 will be cut out, and by this means, approximately the same voltage may be maintained at the two points 86.

While I prefer to use three-light signals for the signals 10 or 11, yet the system would operate if these signals were two-light signals similar to the signals 80. The only difference would be that if signals 10 and 11 were two-light signals there would be no way of indicating to the motorman of a car entering the block whether his car was the first one to enter the block or whether there was another car ahead of him in the block.

In the above-described invention, the indications which are given by the signal are in the nature of fixed indications, and by this term I mean an indication which is unchanging while it is being displayed. Hence when the motorman approaches the signal the fixed or unchanging indication displayed by the signal indicates to the motorman how to proceed. The device is also constructed so that each fixed indication has a distinctive meaning.

I claim:

1. In a block signal system, the combination with a signal guarding a block, of signal-actuating mechanism including a signal-actuating magnet which is responsive only when it is energized a plurality of times in a predetermined time interval, and means thus to energize said magnet.

2. In a block signal system, the combination with a signal guarding a block, of signal-actuating mechanism including a signal-actuating magnet which is responsive only when it is energized a plurality of times in a predetermined time interval, and means actuated by a car entering the block thus to energize said magnet.

3. In a block signal system, the combination with a signal guarding a block, of sig-

nal-actuating mechanism including a signal-actuating magnet which is responsive only when it is energized a plurality of times by currents of different value in a predetermined sequence, and means thus to energize 70 said magnet.

4. In a block signal system, the combination with a signal guarding a block, of signal-actuating mechanism including a signal-actuating magnet which is responsive only 75 when it is energized a plurality of times by currents of different value in a predetermined sequence, and means operated by a car entering the block thus to energize said magnet.

5. In a block signal system, the combination with a signal guarding a block, of signal-actuating mechanism including a signal-actuating magnet which is responsive only when it is energized twice within a 85 predetermined time interval, and means thus to energize said magnet.

6. In a block signal system, the combination with a signal guarding a block, of signal-actuating mechanism including a signal-actuating magnet which is responsive 90 only when it is energized twice within a predetermined time interval, and means operated by a car entering the block thus to energize said magnet.

7. In a block signal system, the combination with a signal guarding a block, of signal-actuating mechanism including a signal-actuating magnet which is responsive only when it is energized by two currents of 100 different values in predetermined sequence, and means thus to energize said magnet.

8. In a block signal system, the combination with a signal guarding a block, of signal-actuating mechanism including a signal-actuating magnet which is responsive 105 only when it is energized by two currents of different values in predetermined sequence, and means actuated by a car entering the block to thus energize said magnet.

9. In a block signal system, the combination with a signal guarding a block, of signal-actuating mechanism including a signal-actuating magnet which is responsive only when it is energized by two currents of different values in predetermined sequence 115 and within a predetermined time interval, and means thus to energize said magnet.

10. In a block signal system, the combination with a signal guarding a block, of signal-actuating mechanism including a signal-actuating magnet which is responsive only when it is energized by two currents of different values in predetermined sequence and within a predetermined time interval, and 120 means actuated by a car entering the block thus to energize said magnet.

11. In a block signal system, the combination with a block, of a signal controlling traffic into said block, a signal-actuating 130

- mechanism including a signal-actuating magnet which is responsive only when it is energized first by a relatively light current and then by a relatively heavy current, and means thus to energize said magnet. 5
12. In a block signal system, the combination with a block, of a signal controlling traffic into said block, a signal-actuating mechanism including a signal-actuating magnet which is responsive only when it is energized first by a relatively light current and then by a relatively heavy current, and means actuated by a car entering the block thus to energize said magnet. 10
13. In a block signal system, the combination with a block, of a signal controlling traffic into said block, a signal-actuating mechanism including a signal-actuating magnet which is responsive only when it is energized first by a relatively light current and then by a relatively heavy current in a predetermined time interval, and means thus to energize said magnet. 15
14. In a block signal system, the combination with a block, of a signal controlling traffic into said block, a signal-actuating mechanism including a signal-actuating magnet which is responsive only when it is energized first by a relatively low current and then by a relatively heavy current in a predetermined time interval, and means actuated by a car entering the block thus to energize said magnet. 20
15. In a block signal system, the combination with a signal at each end of the block, of a signal-setting magnet, a signal-restoring magnet, each of said magnets being responsive only when it is energized a plurality of times in a predetermined time interval, means actuated by a car entering the block to thus energize the signal-setting magnet thereby to set the signal, and means actuated by the car leaving the block to actuate the signal-restoring magnet thereby 45 to restore the signal. 30
16. In a block signal system, the combination with a signal at each end of the block, of a signal-setting magnet, a signal-restoring magnet, each of said magnets being responsive only when it is energized a plurality of times by currents of different values in predetermined sequence, means actuated by a car entering the block to thus energize the signal-setting magnet thereby to set the signal, means actuated by the car leaving the block to thus energize the signal-restoring magnet thereby to restore the signal. 50
17. In a block signal system, the combination with a signal at each end of the block, of a signal-setting magnet, a signal-restoring magnet, each of said magnets being responsive only when it is energized a plurality of times by currents of different values in a predetermined sequence and within a predetermined time interval, means actuated 55
- by a car entering the block thus to energize the signal-setting magnet thereby to set the signals, and means actuated by the car leaving the block thus to energize the signal-restoring magnet thereby to restore the signal. 70
18. In a block signal system, the combination with a signal at each end of the block, of a signal-setting magnet, a signal-restoring magnet, each of which is responsive only when it is energized first by a relatively-light 75 and then by a relatively-heavy current, means actuated by a car entering the block thus to energize the signal-setting magnet thereby to set the signals, and means actuated by a car leaving the block thus to energize the signal-restoring magnet thereby 80 to restore the signal. 85
19. In a block signal system, the combination with a signal at each end of the block, of a signal-setting magnet, a signal-restoring magnet, each of which is responsive only when it is energized first by a relatively-light and then by a relatively-heavy current with- 90 in a predetermined time interval, means actuated by a car entering the block thus to energize the signal-setting magnet thereby to set the signals, and means actuated by a car leaving the block thus to energize the signal-restoring magnet thereby to restore the signal. 95
20. In a block signal system, the combination with a block, of a signal guarding the block, a signal-actuating magnet having a main and an auxiliary armature, means whereby the signal is set when the main armature is actuated by the magnet, a lock for said main armature which is released by movement of the auxiliary armature, and means to energize the magnet so as to actuate the armatures successively. 100
21. In a block signal system, the combination with a block, of a signal guarding the block, a signal-actuating magnet having a main and an auxiliary armature, means whereby the signal is set when the main armature is actuated by the magnet, a lock for the main armature which is released momentarily by movement of the auxiliary armature, and means operated by a car entering the block to energize said magnets so as to actuate first the auxiliary armature 110 thereby to release the lock and then to actuate the main armature thereby to set the signal. 115
22. In a block signal system, the combination with a block, of a signal guarding the block, a signal-actuating magnet having an auxiliary armature which is attracted only when the magnet is energized by a relatively-light current and a main armature which is attracted only when the magnet is energized by a relatively-heavy current, means for locking the main armature from movement except when it is attracted immediately after the auxiliary armature, and means actuated 120 125 130

by a car entering the block to energize said magnet with first a light and then a heavy current.

23. In a block signal system, the combination with a block, of a signal at each end of the block, a signal-setting magnet and a signal-restoring magnet, each of which has a main armature responsive when the magnet is energized with a relatively-heavy current and an auxiliary armature responsive only when said magnet is energized with a relatively-light current, a lock for each main armature which is released momentarily by movement of the corresponding auxiliary armature, means to set the signals when the main armature of the signal-setting magnet is actuated, means to restore the signals when the main armature of the signal-restoring magnet is actuated, means operated by a car entering the block to energize the signal-setting magnet with first a relatively-light and then a relatively-heavy current whereby the main armature of said magnet is unlocked and actuated, and means operated by a car leaving the block to energize the signal-restoring magnet with first a relatively-light and then a relatively-heavy current whereby the main armature is first locked and then actuated.
24. In a block signal system, the combination with a signal at the end of the block capable of giving a plurality of different indications, each of which is fixed or unchanging in character and one of which is in the nature of a "stop" indication, and another of which gives an indication to proceed, of a counting-in and a counting-out device by which cars are counted into and counted out of the block as they enter and leave the same, means to operate said device by a car approaching the signal, and means actuated by the counting-in and counting-out device to cause said signal to change from one to another fixed indication thereby to indicate that said car has been counted into the block.
25. In a block signal system, the combination with a signal at each end of a block normally giving a "stop" indication, but capable of giving unchanging "proceed" and unchanging "proceed with caution" indications, of a counting-in and counting-out device by which cars are counted into and counted out of the block as they enter and leave said block, means to operate said device by a car approaching the signal, and means actuated by the counting-in and counting-out device to cause said signal to change from "stop" indication to "proceed" indication if the block is unoccupied and to change from "stop" indication to "proceed with caution" indication if the block is occupied by another car.
26. In a block signal system, the combination with a signal guarding the block and capable of giving a plurality of fixed indica-
- tions, one of which is the normal indication, of a car-counting device for counting cars into and out of the block as they enter and leave the same, means to operate said device by a car approaching the signal thereby to count said car into the block, and means actuated by said car-counting device when a car is counted into the block to cause said signal to change from its normal fixed indication to a different fixed indication when the car is counted into an unoccupied block and to change from its normal fixed position to a still different fixed indication when the car is counted into an occupied block.
27. In a block signal system, the combination with a signal guarding the block and capable of giving a plurality of fixed indications, of a car-counting device by which cars are counted into and counted out of the block as they enter and leave the same, means to operate said device by a car approaching the signal whereby said car is counted into the block, means actuated by said car-counting device to cause said signal to change from one to another fixed indication thereby to indicate that said car has been counted into the block, and means to cause said signal to return to normal indication when the car has fully entered the block.
28. In a block signal system, the combination with a signal at each end of the block normally giving a "stop" indication but capable of giving "proceed" and "caution" indications, of a car-counting device by which cars are counted into and out of the block as they enter and leave the same, means to operate said device by a car approaching one of the signals whereby said car is counted into the block, means actuated by said car-counting device to cause said signal to change from "stop" indication to "proceed" indication if the block is unoccupied and to change from "stop" indication to "caution" indication if the block is occupied by another car, and means to cause said signal to return to normal indication when the car has fully entered the block.
29. In a block signal system, the combination with a block, of signals guarding said block, signal-actuating mechanism including a car-counting device for counting cars into and out of the block as they enter and leave the same, two contactors at each end of the block situated to be actuated successively by a car and arranged so that the actuation of one contactor is completed before that of the other is commenced, and connections whereby the counting device will be actuated to count a car into the block when the contactors of one pair are operated in one sequence and to count a car out of the block when the contactors of a pair are operated in another sequence.
30. In a block signal system, the combina-

tion with a block, of signals guarding said block, signal-actuating mechanism including a car-counting device for counting cars into and out of the block as they enter and leave the same, two contactors at each end of the block situated to be actuated successively by a car and arranged so that the actuation of one contactor is completed before that of the other is commenced, and 5 connections whereby the counting device will be actuated to count a car into the block and the signals will be set when the contactors are operated in one sequence and said counting device will be actuated to count a car 10 out of the block when the contactors are operated in another sequence.

31. In a block signal system, the combination with a signal guarding the block and capable of giving "proceed" and "stop" indications, said signal normally giving a "stop" indication, of a car-counting device by which cars are counted into and out of the block as they enter and leave the same, means to actuate said car-counting device by 20 a car approaching the signal whereby said car is counted into the block, means actuated by said car-counting device to cause said signal to give a "proceed" indication only when the block is unoccupied and both a 25 "proceed" and a "stop" indication when the block is occupied by a car which has entered from the other end.

32. In a block signal system, the combination with a signal located at one end of a block and capable of giving a plurality of fixed indications, of a car-counting device by which cars are counted into and out of the block as they enter and leave the same, means to actuate said car-counting device 35 by a car approaching the signal to enter the block, and means actuated by said car-counting device to cause said signal to change its indication and to give a single fixed indication when the block is unoccupied and two 40 fixed indications simultaneously when the block is occupied by a car which has entered from the other end.

33. In a block signal system, the combination with a signal guarding the block, of two contactors adapted to be actuated successively by a car entering the block, a car-counting device by which cars are counted into the block as they enter the same, connections whereby said counting device is actuated by one contactor, means actuated by 50 said counting device to cause said signal to give a fixed indication to indicate that a car has been counted into the block, and means to cause said signal to give a "stop" indication 55 when the other contactor is actuated subsequently to the first contactor.

34. In a block signal system, the combination with a block, of a signal guarding the block, means to set said signal by a car entering the block, two contactors adapted to be

successively actuated by a car leaving the block and arranged so that the actuation of one contactor is completed before that of the other is commenced, a normally-open signal-restoring circuit, means to close said signal-restoring circuit by the successive actuation of said contactors in a predetermined sequence only, and means rendered operative when the signal-restoring circuit is closed to restore said signal. 70

35. The combination with a block, of a signal guarding the block, means to set said signal by a car entering the block, two contactors adapted to be successively actuated by a car leaving the block, a signal-restoring circuit normally open at two points, a signal-restoring magnet in said circuit, means rendered operative by the actuation of the contactor which the car first engages when it leaves the block to close the signal-restoring 80 circuit at one point and to maintain it closed, and means rendered operative by the actuation of the other contactor to close said circuit at the other point whereby the signal-restoring magnet is energized and the signal 85 restored. 90

36. In a block signal system, the combination with signal devices guarding the block, means actuated by a car approaching the block and overrunning a signal set against it 95 to count said car into the block, and means operated by said counting-device when so actuated to cause said signal devices to give the same predetermined fixed indication regardless of the number of cars in the block thereby to denote that the counting device has actuated, in addition to the "stop" indication which was overrun by the car. 100

37. In a block signal system, the combination with a block of two signals at each end of the block, two contactors at each end of the block adapted to be actuated successively by cars entering or leaving the block and arranged so that the actuation of one contactor is completed before that of the other is commenced, car-counting devices, means rendered operative by a car entering the block and actuating the two contactors successively to count said car into the block and to set the signal at the opposite end of the block, means actuated by a car overrunning said signal at the opposite end of the block to count said car into the block and to give a fixed indication to this effect without disturbing the signal which was overrun. 110

38. In a block signal system, the combination with a signal guarding the block, of a signal-actuating mechanism including two circuits and which is responsive only when said circuits are momentarily closed in succession in predetermined order, and means thus to close said circuits by a car entering the block. 125

39. In a block signal system, the combination with a signal guarding the block, of a 130

signal-setting mechanism, signal-restoring mechanism including two circuits, said restoring mechanism being responsive only when the circuits are momentarily closed 5 successively in a predetermined order, and means actuated by a car leaving the block thus to close said circuits successively.

40. In a block signal system, the combination with signals guarding the block, of a signal-actuating mechanism including two 10 circuits and which is responsive only when said circuits are closed in predetermined order and within a predetermined time interval, and means actuated by a car entering 15 said block thus to close said circuits.

41. In a block signal system, the combination with a signal at each end of the block, of a car-counting device by which cars are 20 counted into and out of the block as they enter and leave the same, two contactors adapted to be actuated successively by a car, means rendered operative by the actuation of the first contactor actuated by a car entering the block to count said car into the block 25 to cause the signal at the entering end of the block to give a fixed indication that the car has been counted into the block and to set the signal at the opposite end of the block, and means rendered operative by the actuation 30 of the second contactor actuated by said car to change said fixed indication of the signal at the entering end of the block to normal indication.

42. In a block signal system, the combination with a signal at each end of the block, of a car-counting device by which cars are 35 counted into and out of the block as they enter and leave the same, two contactors adapted to be actuated successively by a car, means rendered operative by the actuation of 40 the first contactor actuated by a car entering the block to count said car into the block to cause the signal at the entering end of the block to give a fixed indication that the car has been counted into the block and to set the signal at the opposite end of the block, means 45 rendered operative by the actuation of the second contactor actuated by said car to change said fixed indication of the signal at the entering end of the block to normal indication, and means whereby the actuation of 50 said contactors in the opposite sequence will actuate the car-counting device to count the car out of the block and restore the signal at the opposite end thereof.

43. In a block signal system, the combination with a signal at the end of the block capable of giving a plurality of distinctively 55 different continuing indications, each of a character to convey the desired information independently of any other indication, of a car-counting device for counting cars into and out from the block as they enter and leave the same, means to operate said device 60 by a car approaching the signal, thereby to

count said car into the block, and means actuated by the car-counting device to cause said signal to display to the entering car a distinctive continuing indication different from that normally displayed, which indicates that said car has been counted into the block without reference to said normal indication. 70

44. In a block signal system, the combination with a signal at the end of the block 75 capable of giving a plurality of distinctively different continuing indications, of a car-counting device for counting cars into and out from the block as they enter and leave the same, means to operate said device by a 80 car approaching the signal, thereby to count said car into the block, and means actuated by the car-counting device to cause said signal to display one distinctive indication always for the first car that enters the block 85 when unoccupied and to display another distinctive indication whenever a succeeding car enters the block while it is still occupied by the first car, said last-named distinctive indication being the same for each of said 90 succeeding cars.

45. In a block signal system, the combination with a block, of a normally-closed local circuit at each end of the block, a signal-controlling relay at each end of the block, 95 a signaling circuit connected to said relays and to both the local circuits at points normally of equal potential whereby normally said signaling circuit and the relays therein are deenergized, and means actuated by a 100 car entering the block to vary the potential in one of the local circuits at the point where the signaling circuit connects thereto whereby current will flow in said signaling circuit and operatively energize the signal-controlling relays. 105

46. In a block signal system, the combination with a block, of a normally-closed local circuit at each end of the block connecting the feed to the ground, a resistance in each 110 local circuit, a signal-controlling relay at each end of the block, a signaling circuit connected to said relays and to said local circuits at points of substantially equal potential whereby said signaling circuit and 115 relays are normally deenergized, and means actuated by a car entering the block to provide one end of said signaling circuit with a ground connection of less resistance than that of the local circuit whereby a current 120 will be established in said signaling circuit and the relays will be energized.

47. In a block signal system, the combination with a block, of a normally-closed local circuit at each end of the block, a signal-controlling relay at each end of the block, a signaling circuit connected to said relays and 125 to both local circuits at points normally of equal potential whereby said signaling circuit and relays are normally deenergized, 130

means actuated by a car entering the block to provide said signaling circuit at one end with a ground connection of less resistance than that of the local circuit whereby a current will be established in said signaling circuit and said relays will be energized, a signal operated by said relays, and means actuated by another car which overruns said signal to reestablish normal conditions in the signaling circuit.

48. In a block signal system, the combination with a signal guarding a block, of a car-counting device by which cars are counted into and counted out from the block as they enter and leave the same under all conditions, means actuated by a car entering the block to actuate said car-counting device thereby to count said car into the block and also to set the signal, and means whereby a car overrunning the signal but failing to become counted into the block will also fail to be counted out of the block when it backs out therefrom.

49. In a block signal system, the combination with a signal guarding a block, of a signal-actuating mechanism including two

circuits and which is responsive only when one circuit is broken and the other circuit closed in a predetermined sequence and within a predetermined time interval, and means actuated by a car thus to open and close said circuits.

50. In a block signal system, the combination with a signal at the end of the block normally giving a fixed "stop" indication, but also capable of giving a fixed indication to proceed which is of a character to convey its information independently of the other indication, of a counting-in and a counting-out device by which cars are counted and counted out of the block as they enter and leave the same, means to operate said device by a car approaching the signal, and means actuated by the counting-in and counting-out device to cause said signal to change from the "stop" indication to the other indication, said other indication when displayed indicating that the car has been counted into the block.

In testimony whereof I have signed my name to this specification.

ROY V. COLLINS.

Copies of this patent may be obtained for five cents each, by addressing the "Commissioner of Patents, Washington, D. C."

It is hereby certified that in Letters Patent No. 1,286,946, granted December 10, 1918, upon the application of Roy V. Collins, of Newton, Massachusetts, for an improvement in "Electric Block-Signal Systems," an error appears in the printed specification requiring correction as follows: Page 16, lines 77-78, claim 26, for the word "position" read *indication*; and that the said Letters Patent should be read with this correction therein that the same may conform to the record of the case in the Patent Office.

Signed and sealed this 21st day of January, A. D., 1919.

[SEAL.]

F. W. H. CLAY,

Acting Commissioner of Patents.

Cl. 246—78.
